UNITED STATES PATENT OFFICE.

HENRY T. BLAKE, OF CAÑON CITY, COLORADO.

NECKSCARF.

SPECIFICATION forming part of Letters Patent No. 292,623, dated January 29, 1884.

Application filed September 14, 1883. (No model.)

To all whom it may concern:

Be it known that I, HENRY T. BLAKE, a citizen of the United States, residing at Cañon City, in the county of Fremont and State of Colorado, have invented certain new and useful Improvements in Neckties or Scarfs, of which the following is a specification, reference being had therein to the accompanying drawings.

10 The object of my invention is the production of a scarf or necktie of such construction that it can be easily and securely adjusted in place by the wearer, allowing the collar-button to be utilized as a means for fastening the scarf, while the head of the collar-button will take the place and serve the purpose of the ornamental pin usually worn.

In carrying out my invention I provide the scarf midway of its breadth, near its upper 20 edge, with an eyelet of such size as to admit of the easy passage of the shank of an ordinary collar-button having a detachable head, and I also provide the neckband of the scarf, near its free end, with one or more eyelets 25 corresponding in size to the eyelet in the scarf, the eyelet to be used by the wearer being of such distance from that end of the neckband, which is secured to the scarf, as will permit said neckband to fit snugly around the collar 30 of the wearer. If desired, one or more eyelets may be properly placed near the center of the neckband, to allow the latter to be secured at the back of the neck, also by a detachable-headed button. The scarf is provided 35 on its under side with a loop or hook, to hold that end of the neckband of the scarf in which the eyelet or eyelets are placed in proper position.

In the accompanying drawings, Figure 1 is 40 a front view of a scarf provided with my improvements, the neckband being shown in perspective. Fig. 2 is a sectional view, showing my scarf in its operative relation to the collar, collar-button, and shirt, and Fig. 3 is a back 45 view of my scarf.

A is a scarf, which may be of any ordinary or suitable construction. Near the top of the scarf, about midway of its breadth, I insert an eyelet, *a*.

50 B is the neckband, secured at one end to the scarf in the ordinary manner. The neckband B is provided, near its free end, with one or

more eyelets, *b*. Where several eyelets are inserted in the free end of the neckband they will preferably be placed half an inch apart, so 55 that the length of the neckband to the different eyelets will correspond to the sizes of collars manufactured. If desired, the neckband may be provided near its center with one or more eyelets, *b'*, and where several of these central 60 eyelets are inserted they will be one-quarter of an inch apart, so that the length of the band, in being varied, will be equally distributed on both sides of the center, thus bringing the scarf into a proper central position in 65 front. The eyelets in the center of the neckband will be most desirable when the scarf is to be worn with standing collars, as they will permit the neckband of the scarf to be secured at the back of the neck, so that it cannot 70 work upward on the collar.

C is a hook serving as an auxiliary fastening device for the neckband, said hook being attached to the rear side of the scarf, near its upper end, and on the side of the scarf opposite 75 to that to which the neckband is secured.

D indicates the collar; E, the front collar button or stud, having a detachable head, and E' the back collar button or stud, also having a detachable head, when used in connection 80 with neckbands having eyelets *b'* in the center of the band.

F indicates the shirt.

In arranging my scarf or tie in position, the collar will first be adjusted in the ordinary 85 manner. The neckband will then be placed around the neck of the wearer, and, if desired, secured at the back by a detachable-headed button or stud, as E'. The free end of the neckband will then be brought around to the 90 front, and the shank of the front collar-button E be passed through one of the eyelets *b* in the band and the eyelet *a* in the scarf. The head will then be placed on the collar-button E and the hook C lifted over the neckband, 95 thus securely fastening the scarf in position.

My invention may be used in connection with collar-buttons having pivoted heads by substituting elongated or button-hole-shaped eyelets for the round eyelets herein shown, or 100 by working button-holes in the scarf and band; but the metallic eyelets are considered preferable, as they may be easily and cheaply applied, and are not liable to wear out. The de-

tachable head of the front collar-button may be of any desired ornamentation, and by providing several ornamental heads of different appearance, all adapted to the same shank, the 5 wearer may quickly change what will appear to be his ornamental pin without removing his scarf.

While I have shown my invention as applied to a scarf, it will be obvious that it may 10 also be applied to a bow or "butterfly" or other form of necktie having an attaching band. When the neckbands are provided with only one eyelet at their free ends, they will be sold in regular sizes, the same as collars.

15 With expensive detachable pin-heads a pin and chain might be used as security against loss of the head, should the spring-catch for the head fail to act properly by reason of wear or for other cause.

20 Having thus described my invention, I claim as new and desire to secure by Letters Patent—

1. A necktie or scarf having an eyelet passing entirely through the same near its upper edge, about midway of its breadth, in combination with a neckband secured at one end to the tie or scarf, and having one or more eyelets near its free end, substantially as described.

2. A necktie or scarf having an eyelet passing entirely through the same near its upper edge, about midway of its breadth, in combination with a neckband secured at one end to the tie or scarf, and having one or more eyelets near its free end and one or more eyelets near its center, substantially as described. 30

3. A necktie or scarf having an eyelet passing entirely through the same near its upper edge, about midway of its breadth, and an auxiliary fastening device on its rear side, in combination with a neckband secured at one end to the tie or scarf, and having one or more eyelets near its free end, substantially as described. 40

4. The combination, with the scarf A, having the eyelet *a* and hook C, of the neckband B, secured to said scarf at one end and having one or more eyelets, *b*, near its free end and one or more eyelets, *b'*, near its center, substantially as described. 45

In testimony whereof I affix my signature in presence of two witnesses.

HENRY T. BLAKE.
